TUMBLER

Ernest P. Moslo, Cleveland, Ohio

Application February 23, 1956, Serial No. 40,293

Term of patent 14 years

(Cl. D36—8)

The drawing is a perspective view of a tumbler embodying my design, the drawing being stippled to indicate frosting.

The dominant feature of my design resides in a band of clear diamonds about the waist portion in combination with a clear top band on a frosted tumbler all as shown.

I claim:

The ornamental design for a tumbler, as shown and described.
